UNITED STATES PATENT OFFICE.

OTTO C. RUNGE, OF BALTIMORE, MARYLAND, ASSIGNOR TO STANDARD OIL DEVELOPMENT COMPANY, A CORPORATION OF DELAWARE.

TUBE CLEANER.

Application filed May 7, 1923. Serial No. 637,145.

This invention relates to tube-cleaners such as are used for cleaning tubes of steam boilers, oil heaters, etc., and will be fully understood from the following description taken in connection with the accompanying drawing in which—

Fig. 1 represents a plan of a device embodying my invention;

Fig. 2 is a side elevation;

10 Fig. 3 is a section taken on the line A—A of Figure 1; and

Fig. 4 is an enlarged vertical central section.

Devices of the character contemplated here, 15 in use are subjected to very severe thrusts both endwise and sidewise, and as a result devices commonly on the market are found to develop weaknesses and undesirable lost motion after having been employed for a relatively short time. My invention is directed 20 toward improving the structural elements and assemblage with a view to securing a maximum serviceability in devices of this character.

25 Referring more particularly to the drawing, the reference character 1 designates a body member having transverse projections 2 and screw-threadedly engaged at its base with a support 3. The projections 2 are bored to receive pivot pins 4 which have preferably enlarged heads 5 and are backed up to prevent disengagement by a plate 6. Supported 30 on the pivot pins 4 are the yoke members 7 which carry each a spindle 8 upon which are mounted toothed cutters 9, 10, and 11. Each spindle 8 seats at its forward end in a step bearing 12 in the projecting branch of the yoke member 7, and at its rear end rests against the plate 6. The yoke members 7 are so shaped with relation to the transverse 35 projections 2 as to allow a limited side swing outwardly, any displacement of the spindles 8 during such movement being prevented by the common backing plate 6. As seen, the 40 forward projecting branch 13 of the yoke member 7 is slightly beveled off toward the center so as to present somewhat of a shearing edge against incrustations engaged, while the conformation of the yoke member as a 45 whole gives a well balanced support not only to the rear of the spindles 8 but also at the front where the primary thrust in use is encountered.

The manner of assembling and use of the 50 device will be apparent to those skilled in the

art, it being understood that the cutters 9, 10, and 11 are suitably held in position with relation to the yoke member 7, while the retaining spindle 8 is put in place in each case and the yoke members 7 being duly engaged 60 with the transverse projections 2 and the pivot pins 4 having been inserted, the backing plate 6 is placed against the spindles and pivot pins and the support 3 screwed in place. A suitable driving motor is connected to the 65 device by a screw-threaded engagement 14 in the support, and the device is pushed into the tube to be cleaned, centrifugal force from the rotation holding the yoke members with their cutters in operative engagement with the en- 70 crusted walls of the tube.

Having thus described my invention, what I claim is:—

1. In a tube-cleaner a body member having transverse projections, headed pivot pins 75 through said transverse projections, yoke members mounted on said pivot pins, spindles in said yoke members carrying rotary cutters and supported at their forward ends by step bearings in the yoke members, a backing plate 80 contacting with the rear end of the spindles and the heads of the pivot pins, and a support screw-threadedly engaging the body member and holding the backing plate in 85 position.

2. In a tube-cleaner the combination of a body member and yoke member pivotally supported thereon, said yoke member having a forward branch, a spindle mounted in said yoke member and seated in a step bearing in 90 the said forward branch thereof, rotary cutters mounted on said spindle, and a backing plate for retaining said spindle in position.

3. In a tube-cleaner the combination of a pivotally mounted yoke member, a spindle 95 mounted in said yoke member by a step bearing at its forward end and carrying rotary cutters.

4. In a tube cleaner, the combination of a body member having a transverse projection, a pivot pin in said transverse projection, a yoke member mounted on said pivot pin, said yoke member having a bore extending centrally and toward the rear thereof, and a step bearing at the forward end thereof, a 100 spindle mounted in said bore and bearing, rotary cutters carried by the spindle, and a backing plate in contact with the rear ends of the spindle and pivot pin.

OTTO C. RUNGE,
